UNITED STATES PATENT OFFICE.

JULES GROUVELLE AND HENRI ARQUEMBOURG, OF PARIS, FRANCE.

SPEED-REGULATOR FOR INTERNAL-COMBUSTION ENGINES.

No. 863,916.

Specification of Letters Patent.

Patented Aug. 20, 1907.

Application filed September 24, 1902. Serial No. 124,649.

To all whom it may concern:

Be it known that we, JULES GROUVELLE and HENRI ARQUEMBOURG, trading as LA SOCIÉTÉ JULES GROUVELLE ET H. ARQUEMBOURG, citizens of the French Republic, residing at 71 Rue du Moulin-Vert, Paris, in the French Republic, have invented new and useful Improvements in Speed-Regulators for Internal-Combustion Engines, of which the following is a specification.

This invention relates to improved means, particularly, but not exclusively designed for employment with automobiles, for regulating the speed of internal combustion engines or engines operated by the explosion of successive charges of hydrocarbon vapor mixed with air, the objects being to effect the automatic regulation of the speed of such engines, and to render such speed capable of being limited to suit the conditions for the time prevailing.

In the accompanying drawings, we have illustrated, by way of example, certain arrangements of our improved means for regulating the speed of explosion engines.

Figure 1 is a diagrammatic view showing, in full lines, an explosion engine which is assumed to be of the four cycle type and provided with an ordinary carburetor. Figs. 2 and 3 are diagrams hereinafter more particularly referred to. Figs. 4 and 5 are detail views in vertical section illustrating our improved regulating device. Fig. 6 is a comprehensive view in elevation with partial sections illustrating our improved means for rapidly 30 reducing or accelerating the speed of the motor. Fig. 7 is a plan of the cock employed. Fig. 8 is a section taken on the line $x-x$ and Figs. 9 and 9^a are sections taken on the line $y-y$ in Fig. 6. Figs. 10, 11 and 12 are sections of a form of union for use in the air-pipe.

Assuming our invention to be applied, by way of example, to an engine of the four cycle type, q is a reservoir for the spirit whereof the level is maintained constant by means of a float. b is the atomizing mixer of the carburetor in communication with the reservoir a by way of a pipe. The mixture is supplied to the combustion chamber of the working cylinder d by means of a suction pipe c , the said cylinder being provided with an oil bath casing. e is the exhaust pipe and f the fly-wheel. Now let it be supposed that the engine thus represented is not furnished with any automatic speed-regulating device (that in each complete cycle there is a drawing-in of the explosive mixture, a compression, an explosion and an exhaustion of the waste gases), and that the fly-wheel is provided with a 45 brake which enables the speed of the said engine to be varied at will and by hand. At a convenient part of the suction pipe c , the extremity of a pipe g of comparatively small bore is inserted (as indicated in Fig. 1), the portion of this pipe g , which enters the suction pipe c , terminating in a nozzle, similar to that of a "de Pitot" tube and extending preferably in the direction of the

flow therein, and the said nozzle being disposed as close as may be to the mixture inlet-valve; this small-bore pipe g is further led to a suitably formed chamber h provided with a pressure gage i . We will now examine the variations of the pressures in the chamber h upon the speed of the engine being varied by applying the brake. During the first period which corresponds with the suction, there is produced in the pipe c a partial vacuum and, during the remaining three periods, the pressure therein becomes practically equal to that of the atmosphere. As the engine continues to run, these phenomena occur repeatedly in the same order. Now, the pressures mentioned above are transmitted in succession to the chamber h by way of the pipe g , but, if the said pipe be of sufficiently small diameter and the said chamber h be of sufficient capacity, the said pressures will not have time to be transmitted integrally by reason of the elasticity of the transmitting fluid, and, consequently, the pressure indicated by the gage i will correspond with the mean of the successive pressures which occur, during a complete cycle, in the pipe c .

If p denotes the pressure during the suction period, P the pressure of the atmosphere, and π the pressure indicated by the gage i , the following formula may be arrived at:

$$\pi = \frac{p+3P}{4}$$

With the aid of this formula, it is easy to see that π varies with the speed of the engine; since it is only necessary to show that p varies, because P must remain constant. Now the pressure p depends not only on the resistance to be overcome in the carburetor $a-b$, but also on the velocity of the air, in the pipe c , which, in turn, depends on the speed of the engine, since the volume of air drawn in during the first period is practically constant, while the duration of the aforesaid first period varies with the speed of the engine. It is, moreover, no less easy to prove experimentally that the depression in the chamber h is greater the greater the speed of the engine, and the phenomenon can, therefore, be represented by a curve such as that shown in Fig. 2, in which $o-x$ is the line of the speeds of the engine (at the same time as the line of atmospheric pressure), and $o-y$ is the line of depressions in the chamber h . Now, (as indicated in Fig. 1) connect to the chamber h an air-supply pipe j provided with a cock k , and let us suppose that the diameter of the said pipe j is relatively large in relation to the diameter of the before-mentioned pipe g . Further, let us suppose that the engine runs at a constant speed, and let us inquire why, under these new conditions, the pressures vary in the chamber h when the cock k is turned. When the cock k is closed, there is produced in the chamber h the maximum depression corresponding to the speed of the engine. When,

on the contrary, the cock *k* is completely open, the pressure in the chamber *h* is practically equal to that of the atmosphere, since the pipe *j*, which is comparatively large in diameter, offers practically no 5 resistance to the passage of the air drawn in through the pipe *g* which is of comparatively small diameter. When, finally, the cock *k* is only partially open, there is produced in the chamber *h* a depression of a size included between that of the before mentioned maximum 10 mum depression and that of the atmospheric pressure. It is, moreover, no less easy to prove experimentally that matters occur in this manner, and the phenomenon may, therefore, be represented by a curve such as that shown in Fig. 3, in which *o*—*x* is the line of 15 degrees of opening of the cock *k* (at the same time as the line of atmospheric pressure), and *o*—*y* the line of maximum depressions. As to the point *z*, it corresponds to the complete opening of the cock *k*.

As will be seen, the phenomena represented by the 20 curves in Figs. 2 and 3 are utilized for the regulation of the speed of explosion engines according to our improved method, and only by acting on the admission (in the vessel in which the mixture is produced with or without spraying) of the substance 25 that causes the said explosions (spirit, petrol, alcohol, gas, etc.), and, consequently, dispensing with all more or less complicated parts. It is obvious, therefore, that if, in the example shown in Fig. 1, and by means of a suitable valve, placed at some part of the 30 pipe that connects *a* to *b*, we throttle or even close the passage for the spirit, we shall reduce the power of the explosions, or we shall even entirely suppress the said explosions, so that the engine will run at a reduced speed, or will stop entirely if communication be not re-established between *a* and *b* at the required time. Now, if the bottom of the chamber *h* were composed of a flexible membrane, provided 35 with a spring, or loaded by a weight, it is certain that, under the influence of the partial vacuum produced by the suction stroke of the engine, this membrane would rise or fall according to the direction of the difference of the actions exerted on its two surfaces, and it is these rising and falling movements that are utilized by us to control, in the special arrangement 40 shown in Fig. 4 in sectional elevation, a light valve placed at some part of the pipe that connects *a* to *b*. As will be seen in this figure, the pipe *j*, which is of greater diameter than the pipe *g*, is placed in communication, by way of a rigid or a flexible pipe, with the 45 cock *k* which has a cone and a milled head, for the supply of external air, the said cock being supposed to be placed within reach of the automobile driver's hand, and the bottom of the chamber *h* is formed of a flexible membrane *l* of skin, leather, rubber, thin 50 metal, etc., the central portion of which is held between two metal washers and the edges of which are clamped in the corresponding joint. The upper part of the chamber *h* has, in addition to the unions for the pipes *j* and *g*, a screwed stopper *m* which terminates, 55 on the exterior, in a milled head, and serves as a guide, in the interior, for a rod fixed to the center of the membrane *l*; and for a helical spring *n* which operates the said membrane *l*, and the tension of which can be regulated by turning the before mentioned milled 60 head in one direction or the other. The holes *p* place

the lower surface of the membrane *l* in communication with the atmosphere, and a rod *q*, fixed to the center of the said membrane *l*, bears at its lower end against the valve *r*, which is provided with a helical spring *s* and is adapted to open or close the passage 70 for the spirit. The spring *s* holds the valve *r* on its seat when the rod *q* does not bear on the said valve *r*, and the springs *n* and *s* are adjusted in such a way that the said valve *r*, which is generally more or less open, is at once closed under the influence of a minimum depression in the chamber.

The operation is as follows: Assuming the engine to be running at a normal speed of say 1000 revolutions and that, under these conditions, when the cock *k* in the large-bore pipe is closed, the depression in the 80 chamber *h* is equal to 500 millimeters of water, and only to 50 millimeters of water when the said cock is open, and that the tension of the spring *n* pertaining to the diaphragm *l* is adjusted in such a manner that a depression of 100 millimeters of water in the chamber *h* 85 is required to raise the said diaphragm and close the valve *r* which controls the supply of spirit, it follows that, when the said cock *k* and the said valve *r* are open, the engine will have a tendency to race if the power thereof be greater than the resistance of the vehicle. 90 If, however, the cock *k* be gradually closed, until the depression in the chamber *h* is slightly in excess of 100 millimeters of water, the diaphragm *l* will be caused to rise and effect the closing of the valve *r* so that the supply of the spirit is interrupted, with the result that the 95 speed of the engine is reduced. The tendency now will be for the depression in the chamber *h*, above the diaphragm *l*, to lessen and so, in due course, to effect the re-opening of the valve *r* so as to re-establish the supply of spirit. Thus, the engine will be maintained 100 at a speed of running slightly below 1000 revolutions. By continuing the closure of the cock *k*, the cycle of operations just described will be repeated and the speed of the engine, at each fresh partial closing of the 105 said cock, may be rendered less than the speed immediately preceding. It will thus be seen that the speed of the engine may be varied from racing to a complete stoppage.

The above described method of regulating is particularly adapted for employment in connection with 110 explosion engines for automobiles as indicated, since the said method enables the cock *k* to be placed within convenient reach of the driver, and all more or less complicated mechanism is dispensed with. If preferred, however, the regulation of the speed of the engine and the regulation of the variations of this speed may be simplified. According to this simplified mode of working, let it be supposed that the cock *k* be constantly closed, or that the union for the pipe *j* be dispensed with and the chamber closed as regards such an 115 outlet. The depression which will be produced at each instant in the chamber *h*, while the engine is running at a certain speed, will be precisely that which will correspond, also at each instant, with the same speed, and, therefore, if it be desired to run the engine at a 120 pre-determined speed, it will be sufficient to adjust the tension of the spring *n* in such a manner that its action becomes equal to the action of the depression which acts on the diaphragm *l* at the same speed. This may be accomplished by turning (by hand), in 125 130

the one or the other direction, the screwed stop m and milled head, either directly or through suitable mechanism.

Under certain conditions of working, especially in neighborhoods where the traffic is congested, the necessity frequently arises for rapidly reducing the speed of the motor as well as for rapidly accelerating the same, in order to avoid an obstacle, to keep within, leave, or enter the line of traffic. Compliance with these conditions may undoubtedly be yielded by means of the regulating cock k before referred to, but a certain amount of inconvenience would arise, because this cock would require re-adjustment to the pre-determined speed of running after each such operation. In order to obviate the objections incidental to this method of working and to facilitate the rapid reduction or acceleration of the speed of the motor, we arrange in the large-bore pipe j (or in the extension thereof), between the chamber h and the before mentioned regulating cock k (which it is assumed has been regulated to the speed allowed or possible), another cock u which may be of the following character. In the barrel is arranged a piston u' which normally establishes a through-way in the pipe j . The piston is, however, so constructed that, by completely depressing the same in the direction of the arrow in Fig. 6, its superior cylindrical shut part closes the hollow of the barrel, and, consequently, the pipe j against the atmosphere, while, upon rotating the said piston, as indicated by the arrow in Fig. 7, the interior of the pipe is placed in free communication with the atmosphere, as shown in Fig. 9^a, by way of an aperture u^2 in the barrel. For these different purposes, the piston u' is provided with a combined axial and diametrical bore u^3 . The piston is maintained in its normal position by means of a spring u^4 , preferably arranged about an exterior extension or stem u^5 , the spring being fitted in such a manner that it assists the return of the piston after having been depressed or rotated. A suitable push button or head u^6 and a lateral arm u^7 are formed, or provided, on the extension or stem u^5 , the arm being arranged to engage stops u^8 formed, or provided, on the barrel and thereby limit the rotary movements of the piston. Thus, upon depressing the piston until it arrives at the bottom of its travel, the outer air is prevented from entering the pipe j , with the result that a rapid reduction in the speed of the motor is effected. If, however, the piston be rotated by means of the lateral arm u^7 , so as to bring the aperture u^2 in the barrel into alinement with the diametrical portion of the bore u^3 of the piston, the outer air will have full access to the interior of the pipe j , with the effect that a rapid acceleration of the speed of the motor will result. It will be apparent that the arrangement of the spring u^4 will effect the return of the piston to its normal position upon its release after being either depressed or rotated, as the case may be, the speed of the motor being then regulated by the cock k .

Instead of the opening and closing of the large-bore pipe to the atmosphere being effected by depressing and rotating the piston or plug, the latter may be arranged for rotary movement only, the plug being returned to its normal condition by means of a suitably arranged spring. Figs. 10, 11 and 12 illustrate such an arrangement wherein the unions of the pipe j are

placed opposite each other upon lateral extensions of the barrel. The cock v , provided with a circumferential groove v' and a lateral aperture v^2 , as shown in the drawing, is assumed to be returned by a spring, or its equivalent, to its normal position in relation to the seating w , i. e. in the position shown in Fig. 10, after being rotated by means of a lateral arm (not shown). Upon turning the cock into the position shown in Fig. 11, the ingress to the pipe j of the outer air is prevented, while, upon turning the said cock into the position shown in Fig. 12, the outer air has full access to the said pipe. It follows that various modifications of the cock would readily suggest themselves to the practical mind, and particularly to one familiar with the different varieties of valves used in wind instruments, for the production of music.

The above described apparatus may also be used with an engine having a carburetor wherein the spirit is admitted directly to the spraying mixer by arranging the chamber h on the pipe which supplies the spirit to the said spraying mixer, a stuffing-box or the like being employed in the part t for preventing the ingress of spirit to the chamber below the diaphragm. Where a pump is used for delivering the material (petroleum) through the intermediary of a carburetor or a vaporizer, the same device may be placed at any part of the suction pipe of the pump, care being taken, however, either to balance the supply valve r , so as to remove it from the influence of the vacuum resulting from the working of the pump, or to substitute a cock or equivalent appliance for the said supply valve. In engines wherein a notched distributor or disk, operated by means of a ratchet-wheel, is employed, the apparatus is modified, in the manner illustrated in Fig. 5. - The under side of the diaphragm l is connected with a pawl l' arranged in such a manner as to operate the ratchet-wheel l^2 in accordance with the conditions prevailing in the chamber h , and so to arrest or suppress the distribution or supply of spirit, the stopper m permitting the tension of the spring n to be varied as in the arrangement previously described. In the case of gas engines, the effective area of the supply pipe and of the valve r may be increased, the latter being preferably balanced, and, when the pressure of the gas is practically constant, the openings p in the chamber, below the diaphragm, which communicate with the atmosphere, may be dispensed with. When, however, the pressure of the gas is variable, the lower portion of the chamber is maintained in communication with the atmosphere by means of the said openings p , but the valve-rod is arranged to work through a stuffing-box in the part t so as to prevent the escape of gas.

It will be seen that, by the method herein described, all more or less complicated mechanical transmission parts are dispensed with, not only in the case of automatic regulating devices for explosion engines, but also in the case of the regulation of the said devices by any person intrusted with the care of such engines.

The diameter of the pipe g which projects into the suction pipe e may be varied if found requisite. For instance, it might be of comparatively large diameter and be formed with a restricted orifice, provided its arrangement is such that it offers a resistance by means of a diaphragm, or it may be provided with a

suitable cock, or have its area reduced by any other suitable means.

The adjustment of the spring n may be obtained by means of a rod arranged to slide with slight friction 5 through the cover of the chamber h and be suitably operated.

In the event of a piston being used in place of the diaphragm, any leakage, if inconsiderable, which might occur between the piston and the cylinder wherein 10 it works, would have no detrimental effect on the operation of the apparatus, provided such leakage be relatively small with regard to the quantity of air being drawn, by the engine, through the pipe g .

By the employment of the above described means, 15 the complicated mechanism hitherto considered indispensable for effecting the objects referred to is rendered unnecessary, the manner of regulation being so simple that it can be carried out by even inexperienced operators. Further, it must be noted that considerable advantage is derivable from the employment 20 of apparatus such as we have described, inasmuch as the maximum speed of automobiles may be set with facility, while, in conjunction with all the screw and milled heads, shown in Figs. 4, 5 and 6, stops and seals 25 may be employed, so that the set maximum speed of the motor cannot be exceeded.

We prefer a diaphragm l in lieu of a piston or other

similarly movable part, in the chamber h , but we claim any equivalent of a diaphragm in said chamber h for operating throttling means which regulates the 30 supply of gas or other combustible fluid to the engine.

What we claim as our invention and desire to secure by Letters Patent, is:—

An internal combustion engine, having a conduit to supply it with combustible fluid, means for throttling said fluid, a diaphragm and diaphragm-chamber, the latter connected with the suction of the engine for producing a partial vacuum in the said chamber, means between and connecting the diaphragm with the fluid-throttling means, whereby the former controls the opening of the latter, and 40 means for admitting air to the diaphragm-chamber at will for regulating the pressure on the diaphragm, said last named means comprising a pipe j , open at one end to the atmosphere and at the other end to the diaphragm-chamber, a valve-device u in said pipe consisting of a piston- 45 valve which is slidable and axially rotative, and which has axial and transverse parts, the spring u^4 which holds said valve normally open, the stem of said piston-valve, and means carried by said stem for imparting both a 50 slid-able and rotary motion to the valve.

In testimony whereof we have signed our names to this specification in the presence of two subscribing witnesses.
